H. T. DUNN

FIRE EXTINGUISHING CARTRIDGE SHELL

Filed Jan. 18, 1924

Inventor
Hugh Thomas Dunn

UNITED STATES PATENT OFFICE.

HUGH THOMAS DUNN, OF NEW YORK, N. Y.

FIRE-EXTINGUISHING CARTRIDGE SHELL.

Application filed January 18, 1924. Serial No. 687,076.

To all whom it may concern:

Be it known that I, HUGH THOMAS DUNN, a citizen of the United States, and a resident of New York, in the county and State 5 of New York, have invented certain new and useful Improvements in Fire-Extinguishing Cartridge Shells, of which the following is a specification.

The present invention relates to improvements in fire extinguishing cartridge shells containing fire extinguishing elements, that are propelled with the aid of an explosive charge in guns at fires for the purpose of extinguishing fires.

15 The figures in the drawings are elevations of the shell and explosive charge cap container with novel means of propulsion that will be described in the specifications and claims.

20 Figure 1, 1 the exterior shell casing. 2 the interior shell. 3 the shell head. 4 the interior shell cap projecting striker rod. 5 the orifice plugs in head cap. Figure 2, 6 the cap casing. 7 the cap base. Figure 3, 1 25 the exterior shell casing. 6 the cap casing. 7 the base. 8 the explosive charge. 6 the shell jacket. Figure 4, 1 the exterior shell casing. 6 the shell jacket. 9 the plane. 10 the bracket. 11 the plane struts. 12 the 30 propulsive rod shank. 13 the support brace. 6 the explosive cap. 14 the propulsive gun. Figure 5, 3 the shell head. 4 the projecting striker rod. 5 the orifice plugs. 11 the plane struts. 9 the plane. 15 the vertical 35 plane. 12 the propelling shank rod. Figure 6, 1 the casing cartridge shell. 3 the shell head. 4 the projecting striker rod. 5 the orifice plugs. 6 the shell jacket. 9 the plane. 11 the plane strut supports. 10 the 40 bracket. 12 the propelling shank. 14 the propulsive gun. 10 the bracket. 16 the universal joint. 17 the vertical support. 15 the vertical plane. 18 the base support.

Construction.

45 The interior shells are to be made of glass, earthenware, pottery, or of metal lead or copper, or other noncorrosive material, and are to be filled with sulphuric acid and are 50 to be sealed with a cap with a projecting rod and set within the exterior spherical shell casing in recessed grooves in base and cap of the exterior shell to hold them in position. The exterior shell is made of similar 55 noncorrosive material of spherical form with a screw cap with threads on the con-

necting end of shell casing and on the conical cap's interior edge to connect to the shell casing. The conical cap has central orifice for the projecting rod to extend through 60 and other orifices in the conical curve of the cap with plugs of the same material of construction. The space between the interior shell and interior casing is to be filled with water and bicarbonate of soda of strong 65 solution. The interior of the cap is sealed with wax and the cap screwed on and cemented with waterproof cement also the joint around the projecting rod in the central orifice. The shells are wrapped in cartridge paper around their base and are inserted in brass caps holding a charge of explosive powder. The shells are also inserted in metal jackets with brackets connecting to small planes with connecting struts of metal, 70 and a projecting propelling shank is connected to the shell and jacket with the projecting end of a round circular form to fit snugly into the barrel of guns to propel the shell with the projecting shank. Slight 75 changes may be made in my invention without departing from the spirit or scope thereof.

Operation.

85

The shells may be filled and charged with any fire extinguishing elements or materials and when made of small sizes they may be discharged into fires from ordinary guns and with guns of a special size barrel, and 90 for larger sizes the propelling shank is inserted into the barrels of guns and the explosive charged cap of powder or other explosive material is applied to the propelling shank and the connected planes will carry 95 the shells over a greater distance from the explosive impulse applied to the projecting rod at forest and oil fires where the intense heat prevents firemen from approaching near enough to extinguish them with 100 their present apparatus, and also at fires where no water is available the fire extinguishing shells will provide a means of greater fire protection. When the shell is discharged into a fire and the projecting rod of the shell strikes the burning material it 105 breaks the interior shell and causes the sulphuric acid to mix with the water and bicarbonate and forms carbonic gas, and the exterior shell also strikes and collapses 110 creating a violent mixture forming a great amount of carbonic gas when numbers of

the shells are discharged into fires that will extinguish the fires. The plugged orifices in the head cap of the shell are to act as safety valves in case that the interior shell should 5 be broken by accidental contact in handling the shells as the mixture of the sulphuric acid and water forms carbonic gas the pressure in the interior of the shell will drive out the plugs and allow the carbonic gas to 10 escape without damage or bursting of the shell, and also provides for manual operation by firemen who can push in the projecting rod breaking the interior shell and throwing the shells into fires where possible 15 to do so.

Having thus described my invention, the following is what I claim as new therein.

A fire extinguishing shell, comprising an outer casing and an inner breakable casing, each of which contain fire extinguishing elements, a jacket for the outer container, a striker rod projecting from the inner casing, an apertured head for the outer casing, said apertures containing the said striker rod and plugs and a plane to support said shell with 20 propelling shank rod.

Having thus described my invention I herewith affix my signature.

HUGH THOMAS DUNN.
